UNITED STATES PATENT OFFICE.

IRA E. CLUM, OF LIMA, OHIO.

ANCHOR FOR FENCES.

1,426,044.

Specification of Letters Patent. Patented Aug. 15, 1922.

Application filed December 9, 1919. Serial No. 343,465.

To all whom it may concern:

Be it known that I, IRA E. CLUM, a citizen of the United States, residing at Lima, in the county of Allen and State of Ohio, have 5 invented a new and useful Anchor for Fences, of which the following is a specification.

This invention relates to means for anchoring a fence fabric to the ground at 10 points between the fence posts, thus to prevent live stock from lifting the lower portion of the fence fabric and passing thereunder.

One of the objects of the invention is to 15 provide an anchor of this character which can be readily formed from a strip of sheet metal and which can be easily driven into the ground where it becomes anchored so as to prevent it from being pulled out of the 20 ground.

A further object is to provide a device of this character which can be applied readily to the fence fabric without the use of clips or other fastening devices.

25 With the foregoing and other objects in view, which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

30 In the accompanying drawing the preferred form of the invention has been shown.

In said drawing—

Figure 1 is a side elevation of a portion 40 of a fence fabric having an anchor connected to the lowest strand thereof.

Figure 2 is an enlarged elevation of the anchor in position on a strand.

Figure 3 is a section on line 3—3, Figure 45 2, the position of the anchor when in the soil being indicated by dotted lines.

Referring to the figures by characters of reference I designates a fabric engaging eye formed by bending a metal strip at the center thereof, there being opposed legs 2 extending from this eye and provided with oppositely curved points 3 at the free ends thereof. Segmental barbs 4 are struck out-

wardly from these legs 2 at desired intervals. 55

Under normal conditions the two legs are close together except where the pointed terminals diverge as shown in Figure 3. When it is desired to use the device for anchoring a fence fabric F to the ground at points between the posts P to which the fabric is connected, one or more of these anchoring devices are placed astride the lowest strand of the fence and with their pointed terminals resting on the ground. The anchoring devices are then driven into the ground in the same manner as a stake and as the legs 2 move downwardly the curved lower ends 3 thereof will move apart until, when the anchoring device is driven the entire distance in the ground, these legs will be curved to such an extent as to prevent the anchoring device from being pulled out of the ground. The barbs 4 will still further resist withdrawal of the anchoring device as 75 will be apparent by referring to the dotted position of the anchor in Figure 3.

As the anchor straddles the lowest strand of the fence fabric it is unnecessary to provide any special fastening means. This is 80 especially true in view of the fact that the eye 1 completely surrounds the wire of the fence fabric at all times after the anchor has been applied. Furthermore the connection between the anchor and the fabric is 85 rendered more secure than where fastening means are required. •

What is claimed is:

A fence anchor formed of a single strip of sheet metal bent to provide a central 90 strand receiving eye and legs extending from the eye and having outwardly curved pointed terminals, said legs normally contacting throughout those portions thereof between the eye and the curved terminals, 95 there being barbs upon the legs and diverging toward the eye, said eye being completely closed around the wire of a fence fabric after application thereto.

In testimony that I claim the foregoing 100 as my own, I have hereto affixed my signature in the presence of two witnesses.

IRA E. CLUM.
